BALING PRESS

Arthur E. Modrell, Dearborn, Mo.

Application May 15, 1933, Serial No. 671,063

3 Claims. (Cl. 100—57)

My invention relates to improvements in baling presses.

One of the objects of my invention is to provide a novel baling press with which a bale of compressed material, such as leaf tobacco may be easily made, in which the compressed material therein is protected from the dirt and the weather, which is easily handled, is strong, of compact form, and will withstand rough usage 10 without injury to the contents.

Another object of my invention is the provision of a novel baling press, which is simple, relatively cheap to build, is strong, durable, not likely to get out of order, which provides novel means 15 by which the material to be compressed is easily inserted into the press, and which provides for the easy removal of the completed bale, which is provided with side walls which are movable to a lateral open position in which they will be spaced 20 from the pile of compressed material a substantial distance for the full periphery of the pile, so as to enable the application to the pile while it is under compression of a protecting sleeve for encircling the side walls of the pile, and which baling press is efficient in its operation.

The novel features of my invention are hereinafter fully described and claimed.

In the accompanying drawing, which illustrates my improved bale and my improved apparatus 30 for carrying into effect my improved method of making a bale,

Fig. 1 is a section, partly broken away, on the plane of the line 1—1 of Fig. 2.

Fig. 2 is an enlarged view partly in side elevation, partly in section and partly broken away, of my improved baling press, showing the side walls closed and the pile of material in layers held under compression.

Fig. 3 is a top view of my improved baling press.

Fig. 4 is a reduced side elevation, partly broken away, showing my improved bale completed and resting on the base of the baling press, the side walls of which are shown open and the screw 40 raised.

Fig. 5 is a reduced side elevation, partly broken away, of my improved bale.

Fig. 6 is a top view, partly broken away and reduced, of the completed bale.

Fig. 7 is a reduced plan view of the base of the baling press, partly broken away.

Fig. 8 is an enlarged side elevation of a portion of one of the side walls, showing one of the locking members lockingly engaging one of the standards.

Fig. 9 is a section on the line 9—9 of Fig. 8.

Similar characters of reference designate similar parts in the different views.

My improved baling press is provided with a 60 horizontal base 1 having a central circular raised

portion 2 provided on its upper side with two crossed diametrical grooves 3 for receiving baling wires 4 therethrough.

Extending upwardly from and supported by the base 1 are two standards comprising two cylindrical bars 5.

6 designates each of a plurality of arcuate side walls each having fastened to its outer side two horizontal bars 7 one set of ends of which are provided with eyes 8 pivoted to one of the standards 5, so as to swing from the open position, shown in Fig. 4 and in dotted lines in Fig. 1, to the closed position, shown in Figs. 2 and 3 and in solid lines in Fig. 1.

As shown, there are a plurality of sets of the 15 side walls 6, each set comprising two side walls respectively pivoted to opposite standards 5, and the different sets disposed one above the other.

For releasably locking the side walls in the closed positions, each bar 7 thereof is provided 20 adjacent to its free end with an arcuate portion 9 adapted to embrace the standard 5 opposite to the standard to which the bar is pivoted, and to hold said arcuate portion 9 embracing said standard, the bar has pivoted to it by a pin 10 a 25 locking latch 11 having an arcuate portion 12 adapted to embrace the side of the standard opposite to the side embraced by the arcuate portion 9, Figs. 8 and 9. To lock the latches 11 in the locking positions, there are provided vertical 30 bolts 13 removably fitted one in each pair of bars 7, so as to engage the adjacent pair of latches 11, as shown in Figs. 2 and 9, to hold the latches from disengaging with the standard with which 35 they are engaged.

The upper ends of the standards 5 are connected by a yoke 14 having a central vertical hole in which is vertically slidably mounted a vertical screw 15 having a longitudinal keyway 16 in which is slidably fitted a key 17 fastened to the 40 yoke 14, and which holds the screw 15 from turning, but which permits its vertical sliding movement.

The lower end of the screw 15 is squared and 45 removably fitted in a square hole in the upper side of a circular follower 18, said square hole being designated by 19.

The side walls 6, when closed and locked, as has been described, form with the base 1 a baling chamber in which the follower 18 is vertically slidably fitted against the inner sides of the side walls 6.

For raising and lowering the screw 15, it has fitted on it a circular nut 20 provided on its upper 55 side with a circular row of pins 21 between which is adapted to be inserted a lever 22 for turning the nut. The nut 20 has attached to its under side two lugs 23 which enter and are adapted for circular travel in an annular peripheral groove in 60

the upper central portion of the yoke 14, said groove being designated by 24, thereby holding the nut 20 in one plane of rotation.

The under side of the follower 18 is provided with crossed diametrical grooves 25 adapted to be in vertical register with the grooves 3 in the base 1 for receiving therethrough the baling wires 4 which are employed to bind the bale after it has been formed in the press.

10 In forming the bale, there is placed upon the raised portion 2 of the base 1 a head comprising a circular wooden member 26, or a circular member composed of some other suitable material.

15 The two lower side walls 6 are then swung to the closed position and locked by the latches 11 and bolts 13 to the standard 5 opposite to the one on which the side walls are pivoted. The other side walls are left in the widely open position shown in Fig. 4.

20 The material to be baled, such as loose leaf tobacco 27 is then piled on top of the head 26, with the stems of the leaves against the side walls 6, the leaf tobacco being piled in this manner in layers until the leaves reach the upper edges of 25 the side walls 6. The follower 18 is then placed upon the top of the layers, and the lever 22 is used to turn the nut 20 until the lower end of the screw 15 enters the square hole 19. The screw 15 is then forced further downwardly, thus compressing 30 the tobacco layers. The screw 15 is then raised, by reversing the movement of the lever 22, and the follower 18 is removed and more layers of leaf tobacco are placed upon those which have been compressed, after which the follower is replaced and the screw again lowered to compress the layers last deposited in the baling chamber.

After the portion of the baling chamber which is included within the lower pair of side walls 6 has been filled with compressed tobacco, the screw 40 15 and follower 18 are raised, and the next two side walls 6 above are closed and locked as were the lowermost side walls. Layers of tobacco are then inserted and compressed in the manner already described until the layers of tobacco 45 reach the upper edges of the second set of side walls, following which the screw 15 and follower 18 are again raised and the top two side walls 6 are closed and locked. New layers of tobacco are then laid and compressed upon those already 50 compressed until the compressed tobacco reaches the desired height in the baling chamber, following which the side walls are all swung to the open position, shown in Fig. 4, and the screw 15 is raised and the follower 18 removed temporarily.

55 An upper head, preferably of wood, similar to the head 26 and so designated, is placed upon the top of the pile of compressed tobacco, following which a sleeve of flexible material 28 is slipped over the pile of tobacco. Such sleeve may be 60 burlap, canvas, or other suitable porous material, when the tobacco is first compressed and is still in a not fully dried condition.

Later in the season, after the tobacco has become thoroughly dried, the sleeve may be 65 removed and replaced with waterproofed burlap or other material impervious to air.

After the sleeve 28 has been slipped over the pile, the follower 18 is replaced, and the screw 15 again lowered so as to again compress and hold 70 compressed the pile of tobacco. The sleeve 28

is then nailed to the heads 26, after which the baling wires 4 are extended through the grooves 3 in the base portion 2 and through the grooves 25 in the follower 18 and the ends of the wires fastened together. The square hole 19 in the top of the follower 18 is provided, so that the screw 15 will bring the follower into position for the grooves 3 and 25 to register with each other.

By providing means for releasably fastening each side wall 6 in its closed position independently of the other walls, it may be opened for inspection of the adjacent material without releasing any of the other side walls from its fastened condition.

Many modifications, within the scope of the appended claims, may be made in my invention without departing from its spirit.

What I claim is:—

1. In a baling press, a fixed base adapted to support the lower end of a pile of material to be compressed, two standards, two side walls respectively pivoted to said standards and in the closed position forming with said base a baling chamber for containing said material during the compression of the latter, each side wall having means for being releasably fastened, independently of the other, to the one of said standards opposite to that to which it is pivoted, said standards and said side walls in the open position of the latter being spaced for the full periphery of said pile a substantial distance, and means for engaging the top of said pile for compressing the pile in said chamber.

2. In a baling press, a fixed base adapted to support the lower end of a pile of material to be compressed, two standards spaced a substantial distance from the periphery of the pile, a plurality of sets of side walls which in their closed positions form with said base a baling chamber for containing said material, said sets being disposed one above the other, each set comprising two side walls each pivoted to one of said standards and having means for being releasably fastened, independently of the other, in the closed position to the other standard, the side walls of each set being movable to and from the closed position independently of each other and of the side walls of the other sets, and means for engaging the top of said pile for compressing the pile in said chamber.

3. In a baling press, a fixed base adapted to support the lower end of a pile of material to be compressed, two standards spaced a substantial distance from the periphery of the pile, a plurality of sets of side walls which in their closed positions form with said base a baling chamber for containing said material, said sets being disposed one above the other, each set comprising two side walls each pivoted to one of said standards and having means for being releasably fastened independently of the other, in the closed position to the other standard, the side walls of each set being movable to and from the closed position independently of each other and of the side walls of the other sets, said side walls of said sets in the open position being spaced a substantial distance from said pile, and means for engaging the top of said pile for compressing the pile in said chamber.
